DRIVING ARRANGEMENT FOR THE IMPRESSION CYLINDER PRINTING PRESS

Artur Buttner, Heidelberg, Germany, assignor to Schnell-pressenfabrik A.G. Heidelberg, Heidelberg, Germany, a corporation of Germany

Application August 5, 1958, Serial No. 753,324

Claims priority, application Germany January 31, 1958

2 Claims. (Cl. 101—282)

The present invention relates to cylinder printing presses and more particularly to a drive arrangement for the impression cylinder of cylinder printing machines.

Various driving mechanisms are known for driving the impression cylinder of a printing press to rotate it at an irregular or variable angular speed in one direction. These driving arrangements may be divided into two groups, namely those in which the impression cylinder is continuously driven by means of an independent gear arrangement, and those in which the impression cylinder is driven directly from the type bed and partly by means of a periodically engaging gear mechanism. In the latter type of arrangement there occurs a change of driving means and with increasing operating time of the machine the resultant wear causes vibrations to occur which have a disadvantageous effect on the life and the quality of the printing of the machine. Therefore, it is preferred to have a kind of drive, for the variable speed of rotation of the impression cylinder, in which there is no change of driving means involved.

The present invention concerns a drive arrangement for the impression cylinder where there is no change of driving means involved. It has already been proposed in connection with driving arrangements of this kind to incorporate in the cylinder gear drive, which itself transmits a constant rotary movement to the impression cylinder, a cam-controlled planetary gear mechanism which produces the desired variable rotation of the impression cylinder. However, due to the large number of connecting links required this kind of drive mechanism is unsuitable for high operating speeds.

To avoid the disadvantages of the last mentioned mechanism it is proposed, in accordance with the invention, to employ the combination of non-circular gears for driving the impression cylinder, at a varying speed of rotation, and a synchronizing cammed mechanism, known per se, for accurately synchronizing the type bed reciprocation speed with the peripheral speed of the impression cylinder during the printing period.

A feature of the impression cylinder drive mechanisms in accordance with the invention is that a cam-controlled differential drive, used as a synchronizing device, makes it economically feasible to construct an impression cylinder drive having oval or elliptical gears effecting the variable speed of rotation of the cylinder. While in theory it was heretofore thought possible to variably drive the impression cylinder with oval or elliptical gears it was not practical because such gears cannot be made economically with sufficient accuracy so that the speed of the cylinder is accurately and positively synchronized with the movement of the type bed during the printing period. However, the use of a cam-controlled differential drive makes it possible to use oval or elliptical gears in the cylinder drive arrangement since absolute accuracy of the varying radii need not be maintained and the differential in speeds between the type bed and impression cylinder is completely compensated for by

2

applying a corrective movement to the type bed at the proper time by displacing a rack forming a member of the type bed drive.

The synchronizing of the type bed and impression cylinder is carried out by a pair of cams, forming the control elements of the cam-controlled differential drive, shaped to control the extent and direction of the corrective movement applied to the type bed. This mechanism for applying the corrective or compensating movement to the type bed may also be employed in conjunction with an anti-parallel crank gear drive mechanism which can drive the impression cylinder at a varying speed the same as the drive using varying radii gear.

Other features and advantages of the drive arrangement in accordance with the present invention will be better understood as described in the following specification and appended claims, in conjunction with the following drawings in which

Fig. 1 is a partial side elevation view of the type bed and cylinder drive of a cylinder printing machine having a crank and slide guide for driving the type bed and a drive for the impression cylinder effected by means of varying radii gears for rotating the impression cylinder at a varying angular speed;

Fig. 2 a plan view of the type bed and cylinder drive corresponding to Fig. 1; and

Fig. 3 a partial side elevation view of a cylinder drive mechanism in which the rotation of the impression cylinder at varying angular speed is effected by an anti-parallel crank gear.

The printing press shown in the drawings (Figs. 1 and 2) comprises a frame or base on which a type bed 2 is reciprocated, in known manner, on roller tracks 3 by means of a drive pinion 4, which engages a rack 5 mounted on the type bed and meshes with a rack 6 which is displaceably mounted in the base so that it can be moved longitudinally as later herein described. A connecting rod 7, is connected at one end to the pinion 4 and has its other end connected to a rocking lever 9 by a pin 8. The rocking lever 9 is pivotally mounted at its lower end in the base on pins 10. At either side of the rocking lever 9 there are provided slides 11 and 11' respectively in which sliding blocks 12 and 12' respectively slidably engage. The slide blocks 12 and 12' respectively are pivotally mounted on pins 13 and 13', which are fixed in gear wheels 14 and 14' disposed on either side of the rocking lever 9.

The gear wheels 14 and 14' are mounted on the ends of shafts 45 and 45' which are rotatably mounted in the machine frame 1. When the gear wheels 14 and 14' are rotated the pins 13 and 13' and the blocks 12 and 12' cause the lever 9 to execute a non-uniform or variable swinging movement so that during the printing period of the type bed 2, it is moved slowly and accelerated at the return thereof. The gear wheels 14 and 14' are driven at a uniform speed by the gear wheels 15 and 15' respectively which are firmly connected with a shaft 16 mounted in the base 1. The shaft 16 has a large gear 17 mounted thereon which engages a pinion 18 of a flywheel shaft 19 extending through a wall of the base 1. Outside the frame 1 of the machine the shaft 19 carries a flywheel 20 mounted in the base or frame 1 and is rotatable on a bearing 21. The flywheel 20 is provided with a pulley arrangement 20' by which the shaft 19 can be driven from a power source, not shown, thereby providing drive for the other drive mechanisms.

In the above described example of the construction of the press there is arranged on either side of the rocking lever 9 a gear wheel 14 and 14' respectively. However, it will be understood that it is also possible to use a single slide block guide on one side only of lever 9 by using only one gear wheel 14. The driving ratios,

in both examples, are so chosen that the gear wheels 14 and 14' respectively execute one rotation per printing operation or a complete reciprocation of the type bed.

The drive for the impression cylinder 22 comprises a gear 23 which engages with the flywheel pinion 18. The gear 23 is mounted on a shaft 24, which is rotatably mounted in the machine frame 1 and on which is fixed a pinion 25. The pinion 25 engages with a gear 26 which rotates at a uniform speed of rotation in the direction indicated by the arrow and which has the same pitch diameter as the pair of gears 14 and 14'. Thus with one revolution of the gears 14 and 14', the gear 26 executes a complete revolution with each reciprocation of the type bed. The gear 26 is mounted on a bearing pin 27 which is rotatably mounted in the frame 1 and on the outside of the frame wall carries a gear 28 having varying radii as shown. The gear 28 meshes with a second gear 29 having varying radii which is firmly keyed to an axle journal 30 of the impression cylinder 22. Thus the impression cylinder 22 is rotated in the direction indicated by the arrow at a changing angular speed when the type bed is reciprocated. The shape of the gears 28 and 29 is such that the impression cylinder is rotated at such a variable speed that during the printing period it agrees with the speed of the type bed fairly or substantially accurately therewith, but there is a slight speed differential.

The remaining difference in speed between the type bed and the impression cylinder during the printing period is synchronized by means of a known control gear. The synchronizing is effected by a timed longitudinal displacement of the lower rack 6 in the base 1. For this purpose the rack 6 is connected with two arms 31 and 31' respectively, the free ends of which are slidably mounted in the machine frame 1 at one end thereof as shown in Fig. 2.

On the arm 31 there is rotatably mounted a roller or cam follower 32 and on the arm 31' a roller or cam follower 33. The cam follower 32 cooperates with a cam disc 34, which is mounted on the gear wheel 14, while the cam follower 33 cooperates with a cam disc 35 mounted on the gear wheel 14'. The cam discs 34 or 35 are shaped so that the rack 6 with each revolution of the gear wheels 14 and 14', executes a short reciprocating movement. The extent and direction of the reciprocal movement of the rack corresponds with the necessary correction of the type bed movement during the period of printing thereby causing the type bed movement during the printing period to be completely synchronized with the movement of the impression cylinder.

The configuration of the non-circular gears 28 or 29 may among other things be oval or an elliptical shape. It is also possible to use, as shown in Fig. 3, an anti-parallel crank gear instead of elliptical gears for variably driving the impression cylinder. In this case, the pin 27 which is firmly connected with the gear 25 and which rotates uniformly in the direction indicated by the arrow, has a crank 36 mounted thereon disposed on the outside of the frame wall. A link 37 which is connected to the crank 36 by a pin 38 and by a pin 39 to a crank 40 mounted on the axle journal 30 of the impression cylinder 22, the impression cylinder 22 is rotated in the direction indicated by the arrow. The

impression cylinder is variably driven by this arrangement or drive at exactly the same changing angular speed as if elliptical gears had been used. To overcome the dead center position when the two anti-parallel cranks 36 and 40 respectively are rotating there are provided, in known manner, a ball 41 and a socket 42 at opposite ends of crank 36 and a ball 43 and a socket 44 at opposite ends of crank 40. The ball of each crank engages in the socket of the associated crank and insures continuous rotation of the cylinder. Moreover to eliminate rotation problems in the critical dead center positions it is possible to eliminate the ball and socket arrangement and provide the ends of the cranks with a plurality of small conventional gear teeth, not shown.

While preferred embodiments of the invention have been shown and described it will be understood that many modifications and changes can be made within the scope of the invention.

What I claim and desire to secure by Letters Patent is:

1. In a printing press having a base, a type bed reciprocable on said base, a rotatable impression cylinder co-operating with said type bed and first drive means operative at a selected speed, the combination of second drive means comprising an anti-parallel crank gear mechanism actuated by said first drive means for rotating the impression cylinder unidirectionally at a variable speed, third drive means driven from said first drive means for reciprocating said type bed at such a variable speed that said impression cylinder and the type bed are approximately in registry during each impression period intermediate the ends of each impression stroke of the type bed and a cam-controlled differential drive operatively connected for completely synchronizing the speeds of the cylinder and the type bed during each impression period thereby to cause the cylinder and type bed to be in exact registry during each of said impression periods.

2. In a printing press having a base, a type bed reciprocable on said base, a rotatable impression cylinder co-operating with said type bed and first drive means operative at a selected speed, the combination of second drive means including two co-operative oval gears actuated by said first drive means for rotating the impression cylinder unidirectionally at a variable speed, third drive means driven from said first drive means for reciprocating said type bed at such a variable speed that said impression cylinder and the type bed are approximately in registry during each impression period intermediate the ends of each impression stroke of the type bed and a cam-controlled differential drive operatively connected for completely synchronizing the speeds of the cylinder and the type bed during each impression period thereby to cause the cylinder and type bed to be in exact registry during each of said impression periods.
